HIGH-FREQUENCY DETECTOR

George F. Metcalf, Schenectady, N. Y., assignor
to General Electric Company, a corporation of
New York

Application March 30, 1940, Serial No. 326,933

4 Claims. (Cl. 250—27)

The invention described and claimed herein was initially disclosed in application S. N. 153,602, filed July 14, 1937, as a joint application of this applicant and William C. Hahn.

5 The invention relates to improvements in detectors for use at ultra-short wave lengths, for example, at wave lengths on the order from 5 meters to 5 centimeters or less.

Inasmuch as an adequate explanation of the 10 invention necessarily involves the repeated use of various terms of a more or less technical character, I have in the following paragraphs set forth the meaning which I desire to attach to certain such terms.

15 By "charge density modulation" I mean the controlled production of irregularities in the distribution of charges within a conduction current stream. Thus, a charge density modulated electron beam is a beam in which at any given time 20 the electron density varies from point to point along the beam in accordance with some controlled pattern of variation.

By "velocity modulation" I mean the controlled production of irregularities in charge velocities within a conduction current stream. Thus, a velocity modulated electron beam is a beam in which at any given time the electrons at various points along the axis of the beam are moving with different velocities according to 30 some controlled pattern of variation.

Quantitatively, any type of modulation may be measured as the ratio of the magnitude of the maximum departure of the modulated quantity from its average value to the magnitude of such 35 average value. Thus, a charge density modulated electron beam in which the electron density along the beam axis varies from zero to twice the average density may be said to possess one hundred per cent charge density modulation.

40 In conventional electronic vacuum devices the control member or grid is ordinarily so constructed and arranged as to affect directly the electron emission from the cathode, thus producing a type of "charge density modulation," as hereinbefore defined. It may be shown that the current variations so produced by the grid have the effect of inducing a similarly varying current in the grid circuit. Under ordinary conditions and at low frequencies this induced current 45 which is caused by instantaneous differences in the electron charges approaching and receding from the grid, is relatively small and is approximately 90 degrees out of phase with the grid voltage, so that it produces no appreciable power loss. However, as the operating wave length is

decreased so that the electron transit time becomes appreciable with respect to the reciprocal frequency ($1/f$) of the control grid potential variations, the induced current not only increases but becomes more nearly in phase with the grid voltage. These two effects combine to produce the result that the apparent shunt resistance of the grid circuit varies inversely as the second power of the frequency of the operating voltage. It is for this reason that at very high frequencies (i. e. very short wave lengths) the conventional type of grid attains such a low shunt impedance and involves such a large power loss as to be practically unusable.

In the application Serial No. 153,602 previously referred to, novel discharge devices and methods of operation are described such that the shunt impedance of the control circuit may be maintained at a very high value even when control potentials of very short wave lengths are involved. In one view of the invention disclosed in the said application, this is accomplished by providing control electrode structures which are so constructed and operated as to produce primarily "velocity modulation" of the discharge current 25 without the occurrence of appreciable "charge density" variations in the vicinity of the control electrode. The velocity modulation thus produced is subsequently converted into charge density modulation under conditions which have no 30 adverse reaction on the control electrode circuit.

The present invention is especially concerned with the provision of effective means for accomplishing detection or rectification of a received 35 signal by application of the principles of velocity modulation as described above.

The features of novelty which I desire to protect herein will be pointed out with particularity in the appended claims. The invention itself, together with further objects and advantages thereof, may best be understood by reference to the following description taken in connection with the drawing in which Figs. 1 to 3 are schematic representations illustrating certain basic elements of velocity modulation devices; Fig. 4 is a discharge device embodying one application of my present invention; Figs. 4a, 4b, and 4c are representations useful in explaining the operation of the device of Fig. 4; Fig. 5 is a graphical representation illustrating certain of the characteristics of the device of Fig. 4; and Fig. 6 illustrates a modification of the device of Fig. 4.

In the drawing above referred to I have indicated certain voltage ranges as being suitable for 55

the operation of the various electrodes. It should be understood, however, that the values given are exemplary only and that they may be varied within wide limits even to the extent of 5 changing their order of magnitude.

As explained in the aforesaid application Serial No. 153,602, an important feature of velocity modulation devices consists in the provision of a modulating space which is substantially shielded from the stream source or cathode. By virtue of such shielding, current or potential variations which occur in the modulating space have no tendency to effect changes in the cathode emission or to produce charge density variations in 10 the space.

A modulating space as specified in the foregoing may comprise, for example, a space which is arranged to be traversed by an electron beam, and the entrance and exit boundaries of which 20 are maintained at fixed potentials with respect to one another. Thus, in the particular arrangement shown in Fig. 1, a modulating space is provided between two apertured conducting barriers or diaphragms 10 and 11 which diaphragms 25 are electrically connected to one another and maintained at a definite potential with respect to ground. The chamber thus defined is, in use, traversed by an electron beam 13 which may enter through an opening 15 in the diaphragm 10 30 and leave through a corresponding opening 16 in the diaphragm 11.

In order to produce velocity modulation of an electron beam traversing a modulating space such as that bounded by the diaphragms 10 and 35 11, the potential level of an intermediate region of the space may be cyclically raised and lowered with respect to the boundary potentials at such a rate that the velocity of any given electron in the beam is similarly affected as the electron approaches and recedes from such intermediate region. In connection with the particular structure of Fig. 1, this may be accomplished, for example, by the use of a control electrode in the form of a tube 19 which is positioned between the 40 45 diaphragms 10 and 11 and spaced slightly from each of them. If the potential of this electrode is caused to vary above and below that of the diaphragms with the proper periodicity, as by connection to a source of cyclically varying control voltage 21, effective velocity modulation of 50 55 the transmitted beam may be obtained. The "proper periodicity" as specified in the last sentence is determined by the following considerations.

55 Consider an electron which has just passed through the diaphragm 10 at a moment when the potential of the electrode 19 is at a positive maximum with respect to that of the diaphragm. Such an electron is obviously accelerated in the 60 approach space between the diaphragm and the open end of the electrode tube. In the case illustrated, the interior of the tube 19 constitutes an essentially field-free space, so that the velocity of the selected electron neither increases nor diminishes during its passage through the tube. If, however, the potential of the tube reverses so 65 that the tube is at a potential minimum with respect to the diaphragm 11 at the instant the electron leaves the tube, then the electron is again 70 accelerated in the approach space between the tube and diaphragm. Similarly, an electron which enters the modulating chamber at an instant when the control electrode is negative will be twice retarded as it successively traverses the 75 two "approach spaces." These are effects which

will occur most perfectly if the transit time of the electron through the tube 19 corresponds to a half cycle of the control potential applied to the tube, or to some odd number of such half cycles.

I have so far considered the frequency of the 5 control potential as the independently variable quantity. It will be obvious, however, that for any fixed frequency of control potential the electron transit time itself may be varied to fulfill the condition emphasized in the foregoing paragraph. 10 This may be done as a practical matter either by changing the length of the tube 19 or by varying the average velocity of the electron beam.

Assuming that the various elements have been 15 properly adjusted as I have proposed, it will be seen that there is available an extremely efficient mechanism for producing velocity modulation of an electron beam. With a given peak value of the control potential, certain electrons in the beam will be accelerated by an amount corresponding to a potential variation approaching twice that value, while others will be retarded by an equal amount. The ratio actually existing between the maximum electron acceleration or retardation (expressed in volts) and the peak value 20 25 of the control potential may be called the "velocity ratio" of the control electrode. It will vary somewhat with the electrode geometry, but for the construction illustrated will be only slightly less than two.

30 It may also be noted that the production of velocity modulation by the method and means so far described is accomplished without appreciable power loss in the control circuit. This is due to the fact that the current variations produced in 35 the vicinity of the control electrode structure are actually extremely small so that the resulting current induced in the control electrode is substantially negligible.

The precise form of control electrode structure 40 shown in Fig. 1 is not essential, and in Fig. 2 there is shown another structure which may be alternatively used. In this figure the diaphragms 22 and 23 correspond generally to those already described in Fig. 1. The control electrode structure, however, comprises a pair of wire grids 25 and 26 which are spaced to enclose a region of substantially the same axial extent as the region enclosed by the tube 19 of Fig. 1. Since these members are electrically connected together, this enclosed region constitutes a substantially field-free space; consequently, if the potential of the grids is cyclically raised and lowered with the proper periodicity as previously specified, velocity modulation of a passing electron beam will occur.

55 A still further possible modification of the control electrode structure is shown in Fig. 3, in which the control electrode differs from those previously described in comprising a conducting member of negligible axial extent. This member 60 is illustrated as a ring 30, but may alternatively comprise an apertured diaphragm or other equivalent structure.

With this arrangement the optimum conditions 65 to be fulfilled are somewhat different from those previously postulated. Specifically, it is described that the electron transit time between either of the boundary diaphragms 31 and 32 and the plane of the control electrode correspond to a half cycle of the control potential. This being 70 true, an electron which enters the modulating space at the instant the control electrode has assumed a positive potential is accelerated throughout the duration of its passage from the plane of the diaphragm 31 to the plane of the 75

control electrode. Also, since a voltage reversal occurs as the electron passes the control electrode, it is again accelerated during the entire period of its passage from the plane of the control electrode to the plane of the diaphragm 32. In the same way an electron which enters the modulating space one-half cycle later will be retarded both as it approaches and as it recedes from the ring 30. A similar result is obtained if the transit time between each of the boundary diaphragms and the control electrode is an odd multiple of one-half cycle rather than a single half cycle as described in the foregoing.

The matters set forth in the foregoing paragraphs relate primarily to the production of velocity modulation of an electron beam. The effective utilization of the principle requires the provision of means for subsequently causing the velocity modulation to produce desired effects in an external circuit. The detecting means which comprises my present invention may best be understood by reference to a particular discharge device such as that shown in Fig. 4.

Referring particularly to Fig. 4, there is shown a discharge device which comprises a sealed metal envelope including an elongated tubular portion 40 and a base portion 41 sealed thereto. Within the envelope there is provided means for developing an electron beam of substantially constant average intensity and velocity. Such means may include any known type of "electron gun," and that illustrated constitutes only one example of many possible constructions. In the arrangement shown, the electron source comprises a thermionic cathode including a filamentary heater 43 and an enclosing cylinder 44. Surrounding the cathode as a whole there is provided a focusing electrode in the form of a conducting tubular member 46. This latter element is supported directly by an insulating bushing 47 and indirectly by means of a second tubular member 49 which is rigidly secured to a transverse barrier 51.

In the use of the device the filamentary heater 43 is energized by means of a suitable energy source, such as a battery 52 connecting with the heater through bayonet contacts 54 and 55 and lead-in connections associated therewith. The focusing electrode 46 is maintained at cathode potential or at a potential which is slightly negative with respect to the cathode, and when so charged is effective to concentrate the electrons emitted from the cathode surface into a beam of generally cylindrical outline. Such a beam may be given the desired velocity by impressing an appropriate potential between the cathode and the transverse diaphragm 51. The magnitude of the potential to be applied varies within wide limits depending on the conditions of operation. For a particular case it may be on the order of from 200 to 400 volts and may be provided by means of a battery 57 connected between one of the cathode terminals and the metal structure of the discharge envelope.

Somewhat spaced from the conducting member or diaphragm 51 there is provided a second diaphragm 59 which in the case illustrated is maintained at an identical potential with the first diaphragm by being electrically connected thereto. These diaphragms are respectively provided with central apertures 61 and 62 and in combination define a chamber which is shielded from the beam source or cathode. In the contemplated use of the device this shielded chamber constitutes a modulating space in which the

velocity of the constituent electrons of an electron beam traversing the space may be affected or modulated in a desired manner. Such velocity modulation may be accomplished in any of the ways described in connection with Figs. 1 to 3, 5 and in the particular arrangement illustrated I have shown a tubular control electrode 65 of the particular type illustrated in Fig. 1.

In the use of the device as a detector the potential of the electrode 65 may be alternately 10 raised and lowered by impressing thereon a cyclically varying signal voltage. This may be derived, for example, from a radio frequency input circuit shown as including an antenna 66 and a tuned circuit comprising a condenser 67 15 and an inductance 68. A battery 70 is also employed to impress on the control electrode structure a direct current potential of the same order of magnitude as that impressed on the diaphragms 51 and 59. 20

Assuming the device to be in normal operation, the electron beam issuing from the opening 62 is velocity modulated; that is, it is characterized by successive variations in electron velocity from point to point along the beam. 25 The degree of modulation may be extremely slight if only weak control potentials are available, but it may be changed into charge density modulation of a considerably higher order of magnitude by conversion means now to be 30 described.

Such means may comprise, for example, an electrode 75 positioned in alignment with the opening 62 and adapted to reflect at least the lower velocity component of the beam. This 35 electrode, which is substantially shielded from the modulating space by the diaphragm 59, may be biased, as by a battery 76, to such a low voltage that only approximately one-half of the electron beam is collected, the other half being reflected 40 back along the beam axis. If the beam is velocity modulated as described above, the faster electrons hit the collector while the slower ones are repulsed by it. Since the faster and slower electrons are respectively bunched in alternately 45 spaced groups along the axis of the beam, it will be seen that both the collected current and the reflected current will be charge density modulated.

The method of separating fast and slow electrons described in the foregoing will, perhaps, be better understood by referring to the diagrammatic representations of Figs. 4a, 4b, and 4c. In Fig. 4a, for example, I have shown a 50 stream of electrons which is assumed to be velocity modulated so as to comprise alternate groups of fast and slow electrons. The fast electrons are represented by the groups *a*, and the slow electrons by the groups *b*. The line *d* 55 represents the plane of the collecting anode hereinbefore described. In Figs. 4b and 4c, I have shown the components of the electron beam which have been respectively collected and reflected by the anode *d*. It will be seen that each 60 of these components is characterized by successive variations in charge density and is therefore charge density modulated within the definition of that term previously given herein.

From a consideration of the idealized situation 65 represented in the foregoing it might seem that even the slightest degree of velocity modulation of the electron beam would produce 100 per cent charge density modulation of both the collected and reflected components of current. That this 70

is not so is due in part to the random electron velocity variations inevitably present in the beam even before modulation takes place. Because of such variations the ideal grouping of fast and slow electrons shown in Fig. 4a cannot actually occur, some slow electrons being necessarily mixed with the fast groups and vice versa. This being so, some random fast electrons are collected from even the slow electron groups and some random slow electrons are reflected from the fast groups. As a result, a given amount of velocity modulation produces through the mechanism described an amount of charge density modulation which may be considerably lower than 100 per cent and which is variable with the degree of velocity modulation involved. The actual relation between velocity modulation and charge density modulation is determined by the $e_p - i_p$ static curve of the collector as illustrated in Fig. 5. This curve represents the variation of the collector current i_p which is observed as the collector potential e_p is varied in a continuous manner.

The slope of the curve of Fig. 5 is fixed by random electron velocity variations occurring in the discharge stream, and by certain other considerations including particularly the inclination of the collector with respect to the electron path. It may be very steep for practical tube constructions, so that if such a bias is applied that the collector operates, say, at the point x , substantial amplification may be accomplished. (This mode of operation is more fully described and claimed in my copending application S. N. 385,201,953, filed April 14, 1938.) Alternatively, by operating on a curved portion of the characteristic, say, at point y or z , the relative magnitude of the reversed and collected portions of the beam varies non-linearly with the instantaneous beam velocity, and detection or rectification effects may obviously be obtained. To this end, Fig. 4 illustrates diagrammatically a high impedance detector output circuit comprising (in addition to the battery 76, which is assumed to be of such voltage as to cause operation at point y), a resistor 78 and a blocking condenser 80. As a result of the rectifying effect of the apparatus described, the voltage developed across the terminals of this circuit may be used for the production of audible sounds corresponding to the audio component of the input signal or for the realization of other intelligence-conveying effects depending upon the particular use of the detector.

In some cases it has been found advantageous to tilt the collecting electrode 75 as shown in the drawing to prevent the reversed components of the beam from being returned to the modulating space and thus creating a danger of regenerative oscillations. In the use of this feature, which is the separate invention of Harry L. Thorson, being claimed by him in his application S. N. 264,877, filed March 30, 1939, the returned electrons are collected on the imperforate portion of the header 59.

It is not necessary to the functioning of the invention that the electrode which acts to reverse the low velocity electrons shall also serve to collect the others, and in some cases the alternative arrangement of Fig. 6 is found to be advantageous. Since all the elements in the figure except the output electrodes are identical with those shown in Fig. 4, they are similarly numbered. The output system includes an electron-permeable reversing electrode such as a tubular mem-

ber 88. This is biased to such a voltage that the field established thereby reverses the lower velocity electrons in a manner which varies non-linearly with the instantaneous beam velocity. The electrons of higher velocity pass through 5 the electrode 88 and are collected by the anode 89 (which may, in this case, be biased to a positive potential). A detection circuit is connected to this anode as previously described in connection with Fig. 4. The expedient of tilting the electrode 88 avoids returning the reversed electrons to the discharge space.

In connection with both the constructions which have been described above, it will be understood that the variations which exist in the unreversed portion of the electron beam also occur in equal measure in the reversed portion. Consequently, in either construction detection effects may alternatively be realized by connecting the output circuit to an electrode which is 20 appropriately positioned to collect the reversed electrons.

While I have in the foregoing referred to particular structural embodiments, various modifications may be made by those skilled in the art 25 without departing from my invention. I therefore aim to cover in the appended claims all such variations of form and use as come within the true scope of the foregoing disclosure.

What I claim as new and desire to secure by 30 Letters Patent of the United States is:

1. A detector comprising means for generating a concentrated beam of moving charges, a modulating element having an opening therein to permit passage of the beam therethrough, means 35 including the said element for subjecting the said beam to cyclically varying potential gradients effective to produce variations in the axial velocity of the beam as it traverses the element, electrode structure providing a retarding field acting on 40 the beam after its traversal of the said element for separating the high and low velocity components of the beam by selective reversal of the latter, the strength of the retarding field being such that the relative magnitude of the reversed 45 and unreversed components varies non-linearly with the instantaneous beam velocity, means for separately collecting the said components, and circuit means connecting with one of the said collecting means for utilizing the variations which 50 exist in the collected current.

2. A detector comprising means for generating a concentrated beam of moving charges, a modulating element having an opening therein to permit passage of the beam therethrough, means 55 including the said element for subjecting the said beam to cyclically varying potential gradients effective to produce variations in the axial velocity of the beam as it traverses the element, electrode structure providing a retarding field acting on 60 the beam after its traversal of the said element for separating the high and low velocity components of the beam by selective reversal of the latter, the strength of the said field being such that the relative magnitude of the reversed and 65 unreversed components varies non-linearly with the instantaneous beam velocity, means forming a part of the said electrode structure for collecting the unreversed component of the beam, and circuit means connecting with said collecting 70 means for utilizing the variations which exist in the collected beam current.

3. A detector comprising means for generating a concentrated beam of moving charges, an elongated hollow element arranged to be axially trav- 75

- ersed by the beam, means including said element for subjecting the beam to cyclically varying potential gradients effective to produce high frequency variations in the axial velocity of the beam as it traverses the element, electrode structure providing a retarding field acting on the beam after its traversal of the said element for separating the high and low velocity components of the beam by selective reversal of the latter, 5 the strength of the said field being such that the relative magnitude of the reversed and unreversed components varies non-linearly with the instantaneous beam velocity, means forming a part of the said electrode structure for collecting 10 the unreversed components of the beam, and circuit means connecting with said collecting means for utilizing the variations which exist in the said collected components.

4. A detector comprising means including an

emissive cathode for generating a stream of electrons, a modulating electrode traversed by the stream but sufficiently shielded from the cathode as to be incapable of affecting the electron emission therefrom, means including said electrode for subjecting the stream to axial potential gradients which vary cyclically in accordance with a signal voltage so as to produce corresponding variations in electron velocity, means for reversing the lower velocity components of the stream 10 after its traversal of the said element and for collecting the higher velocity components thereof, said last-named means including means for producing a retarding field of such strength that the number of electrons reversed thereby varies 15 non-linearly with the instantaneous velocity of the stream, and a circuit for utilizing the variations which exist in the said collected components.

GEORGE F. METCALF.
